(57) **CLAIM**

The ornamental design for a upright bracket support as shown and described.

DESCRIPTION

FIG. 1 shows a right hand perspective view of our upright bracket support.

FIG. 2 shows a front elevation view thereof.

FIG. 3 shows a rear elevation view thereof.

FIG. 4 shows a left side elevation view thereof.

FIG. 5 shows a right side elevation view thereof.

FIG. 6 shows a top plan view thereof.

FIG. 7 shows a bottom plan view thereof; and,

FIG. 8 shows a right hand perspective view of the upright bracket support in its use as an article of manufacture with the associated environment in which it is used.

The broken line portions shown in FIG. 8 illustrates environmental subject matter only and form no part of the claimed design.
